METAL SIDING FOR SILOS

Peter Rutten, Plainfield, Ill.

Application July 5, 1938, Serial No. 217,390

3 Claims. (Cl. 20—1.4)

This invention relates to silo structures and the like and more particularly to the walls of such structures.

Several types of farm buildings including silos are customarily built in cylindrical shape and of nearly all types of building material. Some of them are built of wood with staves extending vertically of the cylindrical walls, and usually have hoops encircling the staves at spaced points to give added strength and retain the shape of the structure.

My present invention has for one of its objects the provision of a silo structure wherein a wooden silo wall is encased by metal strips which lie circumferentially of the silo wall with over-lapping adjacent edges which are adapted to cover the nails, screws or other elements utilized to secure the strips to the underlying wall.

Another object of the invention is the provision of sheet metal strips which are relatively narrow and easy to handle, and which are formed substantially flat to permit economical shipping.

Still a further object of the invention is the provision of metal strips for facing silos which are comparatively rigid but which may be bent around the curved circumference of silo walls in such a manner that the applied strips will tightly grip the underlying wooden or other type of wall structure. Not only is the underlying wall gripped tightly but with the edge of one strip overlapping the edge of an adjacent strip this tight overlap is made to bear upon the heads of nails, screws, or other fastening elements in the edge of the under strip so that said fastening elements are positively retained against working loose, and they are protected from the weather.

These and other objects and advantages of the invention will more fully appear from the following description made in connection with the accompanying drawing wherein like reference characters refer to the same or similar parts throughout the views, and, in which:

Fig. 1 is an elevation of the lower portion of a silo with parts of the vertical wooden staves covered by my improved siding and other portions of said staves uncovered;

Fig. 2 is an enlarged fragmentary vertical section through a silo wall showing a portion of a wooden stave and portions of overlapping metal strips;

Fig. 3 is an enlarged fragmentary horizontal section through a portion of a stave and the overlapping ends of the metal strips;

Fig. 4 is an enlarged fragmentary perspective of one of the metal strips; and

Fig. 5 is a view similar to Fig. 4 with an angular corrugation in place of the curved corrugation shown in the other views.

In Fig. 1 there is shown a silo base 6 which is generally of concrete, and upon this base is built a cylindrical silo structure whose walls are indicated as being made up of vertically arranged staves 7 which may be of wood and which usually are interlocked to form a tight wall structure. For the purposes of my invention the wooden stave wall may be the wall of an old silo structure which is to be adapted to my improved construction, or it may be built up new in the same general arrangement of wooden staves.

Arranged circumferentially of the wooden staves 7 is a metallic sheathing made up of a plurality of sheet metal strips 8 which, as shown in Figs. 1 and 4, particularly, are relatively narrow and are adapted to be placed around the wooden walls and secured thereto by any suitable fastening elements such as nails 9 which are adapted to be driven through openings 10 in the upper edges of the strips 8. Each of the strips 8 may be made long enough to completely encircle the silo with its opposite ends overlapping, as shown in Fig. 3. Of course, if desired the strips 8 may be made shorter so that two or more sections of strips are used to encircle the cylindrical wall and in the latter case, of course, the adjacent ends of strip sections would overlap in the same manner as that indicated in Fig. 3. The strips are secured to the wall by first nailing one end to the wooden staves and then bending the strips which are preferably formed flat so that said strips will assume the curvature of the wall. Furthermore, the strips are longitudinally corrugated, as by the curved corrugations 11, to give them more rigidity. The rigidity thus imparted to the strips tends to resist bending movement to some extent, and it has been found that flat corrugated strips of this type which are relatively long and narrow will closely grip the wooden staves lying underneath when said strips are applied by first securing one end and then bending the remainder of the strip around the wall. The gripping action of the strips is comparable to that of bailing wire which will closely grip articles around which it is wound if such wire is bent in a slight curve with the convex portion of the curved wire contacting the article being wrapped.

After the first or lowermost strip 8 has been placed in position around the silo wall and secured by nails or other fastening elements the next strip is placed around the silo with the lower

part of the relatively flat bottom edge portion overlapping the upper edge of the lower strip with the same bending operation to provide tight gripping of the second strip. This second strip 5 will not only tightly fit those portions of the staves with which it is in contact, but the overlapping portion of the lower edge of said strip which lies over the fastening elements of the preceding strip will positively confine said fastening elements against outward movement so that said fastening elements cannot work loose. In addition a weather tight lap-joint is produced 10 and the fastening elements in the edge of the under strip are protected against the weather. 15 Succeeding strips are, of course, applied in the same manner.

It should be noted that the upper rib or corrugation 11, as best indicated in Fig. 4, is positioned comparatively close to the upper edge of 20 the strip 8, and it is so spaced from said edge that the lower edge of the next succeeding strip can be slipped down over the under strip just sufficient distance to form an adequate lap-joint and effectively cover the fastening elements 25 which secure the upper edge of the under strip to the vertical wooden staves.

In Fig. 5 the strip 12 is provided with angular corrugations 13 which are positioned similarly to the corrugations 11 in the strip 8 and function 30 in the same manner.

These metal strips are preferably made of identical shape so that they can be compactly nested for storage and shipment in flat form and then bent into position on the individual silo wall as 35 they are being secured thereto.

As has been brought out before the above described construction can be utilized for covering the walls of old wooden silos, or it can be incorporated in new silo structures. It is preferred 40 that the strips be made of galvanized metal to eliminate the need for painting, and the covering of the nails in the upper edges of the strips conceals practically all of the fastening elements, which, in addition to protecting the nails against the action of the elements, presents 45 a silo wall structure of improved appearance.

It will, of course, be understood that various changes may be made in the form, details, arrangement and proportions of the siding strips 50 without departing from the scope of my invention.

What is claimed is:

1. In a silo construction and the like, a substantially circular supporting wall structure, and wall covering elements comprising a plurality of elongated strips positioned circumferentially of 5 said wall structure to provide substantially continuous circumferential bands, longitudinal corrugations spaced inwardly from the upper and lower edges of said bands, said strips being substantially flat other than at said longitudinal 10 corrugations, the areas between said corrugations and said upper and lower edges being substantially flat, means for securing said flat upper edge portions to said supporting wall structure, and the lower edges of the next adjacent bands 15 overlying the upper secured edges of said bands.

2. In a silo construction and the like, a substantially circular supporting wall structure, and wall covering elements comprising a plurality of elongated strips positioned circumferentially of 20 said wall structure to provide substantially continuous circumferential bands, longitudinal corrugations spaced inwardly from the edges of said bands, the areas between said corrugations and the edge areas of said bands being substantially flat, nails extending through said substantially flat upper edge areas and into said supporting wall structure, and the lower edges of upwardly adjacent bands overlying the upper nailed 25 edges of said bands, and said corrugations being spaced from said upper edges that a predetermined constant overlap is produced.

3. The method of securing elongated circumferential bands to the walls of silos and the like, which includes applying said bands successively 35 by firmly securing one end of a band to the silo wall, bending the band around the silo to conform to the shape thereof and tightly grip the walls thereof, securing the other end of said band to said silo positively securing only the upper edge of said band to said silo, and then applying successive bands in the same manner with the lower edge of the next successive band overlapping the upper edge of the preceding band 40 and its upper edge securing means, whereby each 45 band will have a gripping action upon the underlying silo structure and will also retain the said upper edge securing means against outward displacement.

PETER RUTTEN. 50
